United States Patent Office.

JOHN CROWE, OF GUELPH, CANADA.

Letters Patent No. 104,561, dated June 21, 1870.

IMPROVEMENT IN THREAD-CUTTER FOR SEWING-MACHINE.

The Schedule referred to in these Letters Patent and making part of the same.

To all whom it may concern:

Be it known that I, JOHN CROWE, of Guelph, Ontario, Canada, have invented a new and improved Thread-Cutter for Sewing-Machines; and I do hereby declare that the following is a full, clear, and exact description of the same, reference being had to the accompanying drawing forming a part of this specification.

My invention relates to thread-cutters for sewing-machines, and consists in the peculiar construction and arrangement of the cutter and concavity in the plate of the machine, whereby a more convenient and time-saving device is furnished to the public than those heretofore known.

Figure 1 represents a plan, and

Figure 2 a sectional side view of the plate and cutter.

A is the plate, recessed at *c*, to form a concavity, whose face is curved to a maximum depth at or near the center, and shelved outwardly toward the edges.

B is a knife or small blade, of steel, perforated at the back end, to receive a fastening-screw, which attaches it to the plate. Its point forms a horizontal line with the back, and is flush, or nearly so, with the top surface of the plate. From the point, downward,

the blade-edge forms a curvilinear slope or incline, over which the thread is passed by the operator.

The point of the knife is preferably located so that it reaches to, or nearly to, the center or deepest part of the concavity.

By this construction of recess and knife, and this arrangement of the latter with respect to the former, the thread is readily admitted under the knife, while the edges of the recess enable it to be held taut. By simply drawing it toward the operator, the thread is moved, held, and closely pressed against the inclined cutting-edge, at the same time, and with the smallest possible expenditure of labor.

Having thus described all that is necessary to a clear understanding of my invention,

What I claim as new, and desire to secure by Letters Patent, is—

The knife B, constructed and arranged as set forth, in the concavity C of a sewing-machine plate, for the purpose specified.

JOHN CROWE.
